TIMING MECHANISM IN ROLL-LEAF HOT STAMPING MACHINE
Lewis A. Kingsley, 850 Cahuenga Blvd.,
Hollywood, Calif.
Filed May 14, 1964, Ser. No. 367,301
7 Claims. (Cl. 101—11)

This invention relates to hot stamping machines and more particularly relates to an improved timing mechanism for a roll-leaf hot stamping machine.

In a roll-leaf hot stamping machine of the type used for marking wire, tubing tape or the like, at predetermined intervals to mark the same with a code identification or a similar marking, it is frequently desirable to vary the time interval during which the type and foil engage the work. Such adjustability is particularly desirable when beginning a series of stamping operations to determine the proper interval for a particular type of material, during a run if other conditions should change, and when substituting different types of material.

It is therefore an object of this invention to provide a control for varying the stamping interval of a roll-leaf hot stamping machine.

It is also an object of this invention to provide such a control which is adjustable during the operation of the machine.

It is another object of the present invention to provide such a control which is simple and durable and which is operated in conjunction with the feed mechanism of the machine.

These and other objects and advantages of the present invention will become more apparent upon reference to the accompanying description and drawings in which:

FIGURE 1 is a side elevation of a machine embodying the present invention;

FIGURE 2 is a view taken along lines 2—2 of FIGURE 1;

FIGURE 3 is a cross-sectional view taken along lines 3—3 of FIGURE 2;

FIGURE 4 is an enlarged view of a portion of the machine of FIGURE 1;

FIGURE 5 is a cross-sectional view taken along lines 5—5 of FIGURE 2;

FIGURE 6 illustrates how the stamping interval is adjusted by means of the present invention; and

FIGURE 7 shows a modification of the present invention.

The basic machine with which this invention is concerned is described in detail in my prior United States Letters Patent No. 2,961,950, issued November 29, 1960, the specification of which is incorporated by reference herein. Other details of the machine illustrated in the drawings of this application are fully described in my prior United States Letters Patent No. 2,960,024 issued November 15, 1960, and in my now abandoned patent application Serial No. 215,921, filed August 9, 1962, for "Spacing Mechanism in Hot Roll-Leaf Stamping Machine." The specification of that patent and that patent application are also incorporated herein by reference.

Referring now to the drawings, a hot stamping machine is illustrated having a material stamping assembly, generally indicated at 10, and a material feed assembly, generally indicated at 12, of the type fully described in the aforementioned Patent No. 2,961,950. A stamping actuating assembly, generally indicated at 14, having an air cylinder 16 and an air hose 18 is of the type described in aforementioned Patent No. 2,960,024.

A feed spacing adjustment assembly, generally indicated at 20, is of the type described in the aforementioned patent application and includes a rocking arm 22 pivoted

about an adjustable pin or fulcrum 24. The rocking arm 22 is actuated by a shaft 26 having a bifurcated end to which the arm 22 is connected by a pin 28. The shaft 26 reciprocates in a sleeve 30. The mechanism for adjusting the position of the fulcrum 24, described in my aforementioned application, is controlled by a knob 32 on control panel 34. Power for operating the various mechanisms of the machine is provided by a motor 36.

The shaft 26 is reciprocated in the sleeve 30 by means of a crank arm 44 which is connected to the shaft 26 by means of a pin 46. The other end of the crank arm 44 is pivotally pinned to a disc or wheel 48 which is eccentrically mounted on a shaft 50.

A plate 52 is mounted on the bed of the machine in the vicinity of the disc 48 and has mounted thereon a block 54 having a horizontal channel 56 formed therein. The channel is covered by a cover plate 58 and has a slider 60 mounted for sliding movement therein. The slider 60 has a slot 62 formed therein in which is positioned a spring 64 which cooperates with a pin 66 mounted on the block 54 to urge the slider 60 toward the rear of the channel 56.

A threaded member 68 is threaded into a cooperating passageway in the slider 60 and is journaled in a bushing 70 force fit into an end plate 71 mounted on the block 54 and cover plate 58. A collar 72 is fixedly attached to the protruding end of the threaded member 68 by means of a set screw 74.

The other end of the slider 60 has a plate 76 fixedly mounted thereon. The plate 76 extends beyond the block 54 and has mounted thereon an air valve assembly 78 by means of the threaded neck 80 of the assembly 78 and a pair of nuts 82 and 84. The air valve assembly 78 includes a body 86 integral with the neck 80. The body 86 has a valve chamber 88 formed therein which is in communication with an inlet passage 90 and an outlet passage 92. These passageways are respectively connected to conduits 94 and 96.

A valve body 98 is slidably mounted in the chamber 86 and is adapted to cooperate with a valve seat 100 formed at one end of the chamber to break fluid communication between the inlet passage 90 and outlet passage 92. A spring 102 normally biases the valve body 98 into engagement with the seat 100. The spring 102 is held in position by a screw 104. An O-ring 106 is provided to maintain the integrity of the valve chamber 88.

The valve body 98 is provided with an extension 108 which passes through a passageway in the body 86 and extends into a passageway formed in the neck 80. A sliding member 110 is slidably mounted in this passageway and is threaded onto the extension 108. The sliding member 110 is provided with an O-ring 112 to prevent escape of air from the valve chamber 88. The end of the sliding member 110 is bifurcated and carries a pin 116 on which is rotatably mounted a roller 117.

A flexible cable 118 is connected to the collar 72 by means of any suitable coupling 120 and extends into the control panel 34. A knob 122 on the control panel is operatively connected to the cable 118 in any manner well known to those skilled in the art so that rotation of the knob 122 is transmitted through the cable 118, coupling 120 and collar 72 to the threaded member 68.

By turning the knob 122, the slider 60 can thus be moved in the channel 56. This movement is coupled to the air valve assembly 78 by means of the plate 76 and thus serves to move the roller 116 closer to or further from the rotating disc 48. Engagement of the periphery of the disc 48 with the roller 116 will, of course, cause the valve body 98 to move away from the valve seat 100 and permit the flow of pressurized air from the inlet passage 90 to the outlet passage 92. The conduit 96 connected to the outlet passage 92 can be coupled in any suitable

fashion to the air hose 18 and thus the movement of the valve body 98 will cause the air cylinder 16 to actuate the material stamping assembly.

FIGURE 6 shows how the movement of the roller 117 together with the eccentric mounting of the disc 48 changes the stamping interval of the machine. As the roller 117 is moved further away from the shaft 50 upon which the disc 48 is mounted, the contact time between the disc 48 and roller 117 is reduced and consequently the air valve is open for a shorter time period. It can be seen that very accurate control of the stamping interval can be achieved by turning the knob 122. For coarser control, the air valve assembly 98 can be moved relative to the plate 76 and then again fastened into position by nuts 82 and 84. The timing interval control provided by the knob 122 can be exercised at any time and does not in any way interfere with, or require the stopping of, the operation of the machine.

A modification of the invention is shown in FIGURE 7. In this figure, the contact arm 124 of an electric switch 126 has been substituted for the roller 116. The electric switch is adjustably mounted on the plate 76 in place of the air valve assembly 78, and electrical leads from the switch connected to a solenoid operated valve (not shown) which serves to interrupt the air supply to the air cylinder 16. Movement of the switch 126 closer to or further from the eccentrically mounted disc 48 varies the stamping interval in the same manner as did moving the roller 117 in the embodiment shown in the other figures.

The invention may be embodied in other specific forms not departing from the spirit or central characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

I claim:

1. In a roll-leaf hot stamping machine of the type having a pressure cylinder actuated stamping mechanism for marking material intermittently advanced through the machine, and means for supplying fluid under pressure to said cylinder for causing the operation thereof, the combination of a valve coupled in said fluid supplying means to control the flow of fluid therethrough, a shaft, means for rotating said shaft, a disc eccentrically mounted on said shaft, valve actuating means coupled to said valve for opening said valve, said valve actuating means including a roller mounted on a shaft coupled to the body of said valve whereby engagement of said roller by said disc causes said valve to be opened, a block mounted on said machine, a slider slidably mounted on said block, remotely controllable means for moving said slider relative to said block, and a plate mounted on said slider, said valve actuating means being mounted on said plate for movement relative to said disc to vary the time interval of engagement between said disc and said engageable means.

2. The combination of claim 1 wherein said engageable means is an electric switch operable by engagement of said disc to cause said valve to be opened.

3. In a roll-leaf hot stamping machine of the type having a pressure cylinder actuated stamping mechanism for marking material, means for supplying fluid under pressure to said cylinder for causing the operation thereof, and

a mechanism for intermittently advancing said material through said machine including a reciprocating mechanism for pivoting a rocking arm about a fulcrum, the combination of a valve coupled in said fluid supplying means to control the flow of fluid therethrough, a shaft, means for rotating said shaft, a disc eccentrically mounted on said shaft, a crank arm drivingly coupling said disc with said reciprocating mechanism, valve actuating means coupled to said valve for opening said valve, said valve actuating means including means engageable with said disc to cause opening of said valve, a block mounted on the bed of said machine, a slider slidably mounted on said block, remotely controllable means for moving said slider relative to said block, said remotely controllable means including a member having one end threadedly cooperating with said slider to move said slider relative to said block and the other end extending beyond said block, a collar fixably mounted on said other end, and cable means coupled to said collar for causing rotation of said member and lateral movement of said slider, a plate mounted on said slider, and means mounting said valve actuating means on said plate, movement of said slider and said plate causing movement of said engageable means relative to the periphery of said disc to vary the time interval of engagement between said disc and said engageable means.

4. The combination of claim 3 wherein said slider slides in a channel formed in said block and is provided with a slot, said block is provided with a pin that extends into said slot, and a spring is provided in said slot for cooperating with said pin to urge said slider toward said threaded member.

5. The combination of claim 4 wherein said engageable means is a roller mounted on a shaft coupled to the body of said valve whereby engagement of said roller by said disc causes said valve to be opened.

6. The combination of claim 4 wherein said engageable means is an electric switch operable by engagement of said disc to cause said valve to be opened.

7. The combination of claim 5 wherein said valve actuating means includes a body portion and a hollow neck portion, said neck portion being adjustably mounted on said plate, said body portion including a valve chamber having inlet and outlet passages and a valve seat adjacent said passages, said valve body being slidably mounted in said chamber and engageable with said seat for blocking fluid communication between said passages, said coupling shaft extending through said hollow neck, and spring means in said chamber urging said valve body into engagement with said seat.
